PORTABLE DISK ABRADING MACHINE

Arthur N. Emmons, Nedrow, N. Y., assignor to
The Porter-Cable Machine Company Inc.,
Syracuse, N. Y., a corporation of New York

Application July 24, 1937, Serial No. 155,507

3 Claims. (Cl. 51—177)

This invention relates to improvements in portable, power operated, hand-manipulated disk abrading machines of the type referred to in my Patent No. 1,983,277, issued December 4, 1934.

The invention has as an object a machine of the type referred to embodying a construction which materially improves the efficiency of the dust collecting system and the general operation and manipulation of the machine.

The invention consists in the novel features and in the combinations and constructions hereinafter set forth and claimed.

In describing this invention, reference is had to the accompanying drawings in which like characters designate corresponding parts in all the views.

Figure 1 is a front elevational view of the machine embodying my invention.

Figure 2 is a front elevational view of the machine shown in Figure 1 arranged in inverted position.

Figure 3 is a vertical sectional view of the machine.

Figure 4 is a bottom plan view of the machine.

Figure 5 is a bottom plan view of the lower end section of the machine with the abrading disk and dust baffle removed.

Figure 6 is a view taken on line 6—6, Figure 3, with the suction fan removed.

Figure 7 is a view taken on line 7—7, Figure 3.

The embodiment of the invention, as here shown, consists of a substantially cylindrical casing 10 open at each end and formed or provided with a partition 11. The upper end portion of the casing 10, above the partition 11, constitutes a fan chamber 12, and the lower portion of the casing forms a motor chamber in which the field 13 of the motor is mounted and secured by means of screws 15.

The machine further includes a lower end or base section 16 detachably secured to the lower end of the casing 10, as by screws 17. The upper side of the base 16 is provided with an upwardly extending annular flange 18 which extends into the open end of the casing and aids in maintaining the base and casing in predetermined axial relationship.

The base is formed with a gear compartment 20 in which are arranged gears constituting the motion transmitting means between the motor and the abrading disk. The gear compartment 20 opens through the bottom end of the base, and the opening is provided with a closure in the nature of a cap 21 detachably secured to the

base as by screws 22 threading into holes 23, see Figure 5. The cap 21 and base 16 are provided with axially aligned apertures to receive anti-friction bearings 24 in which a stub shaft 25 is journaled. The base 16 and the partition 11 in the casing 10 are also formed with axially aligned apertures to receive anti-friction bearings in which armature shaft 26 is journaled. The lower end of the armature shaft 26 extends into the gear compartment 20, and a pinion 27 is mounted thereon and arranged to mesh with gear 28 secured on the stub shaft 25. The stub shaft 25 extends outwardly or downwardly through the cap 21, and a suitable disk is secured thereto, and on the face of which is secured an abrasive sheet 30 which may be removed or renewed by removal of the screw 31 threading into the end of the shaft 25.

The casing 10 is also provided with inwardly extending bosses 33 arranged in diametrical relationship immediately below the partition 11. The bosses 33 are formed with suitable apertures to receive the brush holders 34.

The upper end of the armature shaft 26 extends upwardly through the partition 11 into the fan chamber 12, and a fan 36 is mounted thereon. The rear side wall of the chamber 12 is formed with a discharge opening 37 communicating with a short conduit 38 on which is detachably secured a dust collecting bag 39, as by ring 40. The upper end of the casing or fan chamber is closed by a discoidal closure or plate 41 detachably secured to the casing as by screws 42. The plate 41 is provided with an annular recess adjacent its periphery in which is mounted a ring 43 of yielding material, such as rubber.

The general arrangement and relationship of the machine is such that it may be inverted and supported on the plate 41, as indicated in Figure 2. It will be understood that the sheets of abrading material 30 wear out rapidly and necessitate frequent replacement. Heretofore in machines of this type, the replacement of the abrading sheets has been a tedious and somewhat difficult task due mainly to the fact that the machine would not stand in inverted position, and if inverted on the floor or surface being finished, due to the instability in this position, the floor or surface would be considerably marred during the changing operation. This is avoided by the rubber ring 43, and due to the comparatively large diameter of the plate 41 and the balanced arrangement of the machine, it is entirely stable in inverted position.

The flange 18 on the upper side of the base 16 extends inwardly adjacent the periphery of a fan 46 secured to the lower end of armature shaft 26, and the flange 18 is provided with a discharge opening 47. The casing 10 is formed with a plurality of openings 48 immediately beneath the partition 12, and while the motor is in operation, the fan 46 draws air inwardly through the openings 48, downwardly around the field and armature of the motor, and outwardly through the discharge opening 47.

In order that the machine may be conveniently used in poorly lighted places, it is equipped with a lamp arranged to direct its rays downwardly and forwardly in front of the cutting portion of the abrading disk. As here shown, a lamp receptacle 50 is secured to the front side of the casing 10 adjacent the lower end thereof, and the receptacle and lamp 51 are enclosed by a housing 52 detachably secured to the front of the casing as by screws 53, the lower end of the housing being provided with an opening 54 to permit the rays from the lamp 51 to be directed upon the work being finished. The outlet opening 41 of the chamber enclosing fan 46 is arranged adjacent lamp 51, and the air is also discharged through the light opening 54 of the lamp housing 52. This arrangement provides for the circulation of clean air around the lamp 51, and prevents the collection and accumulation of fine dust rising from the abrading disk, settling on the lamp and decreasing its efficiency. The lamp 51 is controlled by a small switch 56 located in the base portion of one of the handles 57 secured on either side of the casing 10 and extending rearwardly for convenient manipulation of the machine.

The base 16 is formed with a depending annular flange 60 of substantially arcuate formation and which extends around the major portion of the periphery of the abrading disk, and the ends 61 extend inwardly in close proximity to the periphery of the disk, see Figure 4. The lower edge of the flange 60 extends in angular relationship to the axis of the machine. That is, downwardly and rearwardly, as indicated at 62, Figure 3. The portion of the abrading disk extending forwardly from the flange 61 constitutes the cutting portion of the disk. That is, the portion which is in contact with the surface being finished during the finishing operation. This requires a slight tilting forward of the machine, and the angular arrangement of the lower edge of the flange 60 maintains the flange in close proximity to the surface being finished during the finishing operation. The base 16 may be provided with casters 64 movably mounted in housings 65 secured to bosses 66 formed on the rear side portions of the base.

The flange 60 forms a dust collecting chamber about the abrading disk, and the rear portion of this chamber extends upwardly on each side of a rib 68 and communicates with arcuate openings 69 extending through the upper side of the base, see Figure 5. The dust collecting chamber and the arcuate opening 69 are connected with the fan chamber 12 by means of arcuate extending ducts 70 formed in the rear side wall of the casing 10 and connecting at their upper ends with an arcuate chamber 71 extending upwardly and inwardly toward the armature shaft and communicating with a central opening 72 in the bottom of the fan chamber 12, see Figure 6.

When the machine is in operation, the fan 36 creates a partial vacuum in chamber 71, ducts 70, and the lower dust collecting chamber and

the dust created by the abrading disk and discharged within the flange 60 is drawn upwardly and discharged through the opening 37 into the bag 39. This general arrangement also serves the dual purpose of materially aiding in cooling the motor inasmuch as the ducts 70 are arranged in heat conducting relationship to the field of the motor.

Preferably, the cap 21 is provided with a radially extending flange 75 also of arcuate formation and which extends radially from the periphery of the abrading disk toward the casing or flange 60, and terminates in relatively close proximity thereto to form a restricted opening 76. This arrangement intensifies the vacuum created by fan 36, and effects a more rapid and complete collection of the dust as it is discharged from the abrading disk. Preferably, the flange 75 is arranged relatively close to the plane of the abrasive sheet 38, as shown in Figure 3. Also, the machine may be provided with a discoidal guard 77 fixedly secured to the base 16 or cap 21 by screws 78.

It will be observed that the structure described is particularly compact and rigid, and that the dust collecting system is particularly efficient in that while the discharge opening 37 is arranged adjacent the top of the machine permitting a convenient location for the attachment of bag 39, the dust travels a minimum distance and is effectively gathered up and discharged into the bag 39.

What I claim is:

1. A portable hand manipulated disk sanding machine comprising a substantially cylindrical casing, the lower end of said casing being formed with a depending arcuate wall, an abrading disk journaled in the lower end of the casing with the periphery of said disk arranged in spaced apart relationship to said wall, an arcuate housing overlying said disk and being detachably secured to the lower end of said casing, said housing being formed with a radial flange extending from the periphery of said disk toward said arcuate wall and terminating in spaced apart relationship thereto, suction means arranged in the casing and having an inlet opening in the lower end of the casing above said housing, a motor mounted in the casing, and motion transmitting means operatively connecting said motor and abrading disk.

2. A portable hand manipulated disk sanding machine comprising a cylindrical casing provided at its lower end with a gear compartment, a motor mounted in the casing with the rotor shaft extending into said compartment, a shaft journaled in the lower end of the casing and having one end extending through the bottom of the casing, an abrading disk mounted on the extending end of said shaft, gearing arranged in said gear compartment and operatively connecting the motor shaft and said second shaft, a cap detachably secured to the bottom of the casing and forming a closure for said gear compartment, said cap extending radially over the top of said disk and forming a housing therefor and being provided on its periphery with a radially extending flange terminating in spaced apart relationship from the periphery of the casing, suction means carried by the casing and having an inlet opening in the lower end of the casing above said flange.

3. A portable hand manipulated disk sanding machine comprising a substantially cylindrical casing, an abrading disk journaled in the lower end of the casing on an axis to one side of the

axis of said casing with the periphery of said disk arranged in spaced apart relationship to the lower end of said casing, said casing being provided with a baffle plate overlying the upper side of said disk and being arranged in spaced apart relationship thereto with the peripheral margin of said baffle plate extending radially outwardly from the periphery of the disk toward said casing and terminating in spaced apart relationship thereto to

5 form a comparatively narrow arcuate slot extending adjacent the periphery of the casing, suction means arranged in the casing and having an inlet opening connected with said slot, a motor mounted in the casing, and motion transmitting means operatively connecting the motor with said disk.

ARTHUR N. EMMONS.
